DES. 1998

Frederick Bailey of New York, N.Y.

Letters Patent No 1998-Dated Nov 15 1864

Design for an Ink Bottle

The schedule referred to in these Letters Patent and making part of the same.

of all whom it may concern:

But know that I, Frederick Bailey, of the City, County and State of New York, have invented a certain new design for an Ink Bottle, of which the following is a full, clear and exact description, reference being had to the accompanying drawing, making part of this specification, in which is represented a perspective view of my ink bottle.

The object of my invention is to produce an ornamental and unique design for an ink bottle, and consists in a barrel placed on its belge on a base or stand, the mouth of the bottle being placed uppermost at the bung and my trade mark on one or both heads of the barrel.

To enable others skilled in the art to understand and use my invention, I will proceed to describe the manner in which I have carried out.

In the said drawings A represents a barrel, placed upon its belge on a base or stand B, the mouth a, of the bottle being formed at the bung.

The heads of the barrel are thus exposed to view and furnish a conspicuous place upon which to exhibit my trade mark, viz. "Bailey's Anticorrosive Ink," which may be placed on one or both heads.

2

DES. 1998

Claim

What I claim as my invention and desire to secure by Letters Patent is the above design for an Ink Bottle, consisting of the barrel A resting on the base B and having my trade mark (Bailey's Antiseptic Ink) on one or both heads of the base substantially as set forth.
